UNITED STATES PATENT OFFICE.

SAMUEL S. COOPER, OF LANDGRAFF, WEST VIRGINIA.

TROLLEY-POLE HEAD.

1,353,381.

Specification of Letters Patent. Patented Sept. 21, 1920.

Application filed May 16, 1919. Serial No. 297,475.

To all whom it may concern:

Be it known that I, SAMUEL S. COOPER, a citizen of the United States, residing at Landgraff, in the county of McDowell and State of West Virginia, have invented certain new and useful Improvements in Trolley-Pole Heads, of which the following is a specification.

This invention relates to improvements in trolley pole heads and is especially directed to the heads of trolley poles upon mine locomotives although it is not limited to this specific use as it may be employed upon other trolley poles if found desirable.

In the operation of mine locomotives serious accidents are not infrequently caused through the catching of the trolley pole head in the frogs of the overhead trolley system, the guy wires, and other parts in the path of movement of the pole when the pole leaves the wire. When this occurs the pole is either torn loose from the locomotive or the trolley wires are torn down, and even if there are no more serious results, delay is occasioned in the making of the necessary repairs. The present invention therefore has as its primary object to provide a trolley pole head so constructed that in the event the head is caught in a frog, or leaves the trolley wire and strikes an obstruction, no injury to the head or wires or to the crew of the locomotive will be caused.

Briefly stated, the invention resides in forming the head in two sections normally held connected or in assembled relation by a means adapted to yield when one of the sections comes into engagement with an obstruction or is caught in a frog, so as to permit of separation of the engaged section from the other section which is permanently carried by the pole, and another object of the invention is to provide for proper conduction of the current from the trolley wire to the locomotive by a means which will not in any way interfere with the separation of the sections of the head under emergency conditions.

In the accompanying drawings:

Figure 1 is a side elevation of a trolley pole head constructed in accordance with the present invention;

Fig. 2 is a sectional view on the line 2—2 of Fig. 1;

Fig. 3 is a similar view on the line 3—3 of Fig. 1;

Fig. 4 is a rear elevation of the harp of the head detached.

In the drawings the numeral 1 indicates the trolley pole upon which the head is mounted and the said head, which is indicated in general by the numeral 2, comprises two sections one indicated by the numeral 3 and the other by the numeral 4. The section 3 of the head is in the nature of a ferrule 5 which is fitted onto the end of the pole 1 and secured in place by screws, rivets, or any other suitable fastening elements indicated by the numeral 6 and as clearly shown in Figs. 2 and 3 of the drawings. As this section is to be a conductor of the electrical current, it is, of course, formed of metal, and in order that the usual conducting cable (not shown) may be electrically connected therewith, a boss 7 is formed upon the under side of the ferrule 5 and has a socket or opening 8 formed therein to receive the terminal of the cable, the terminal being secured by one or more binding screws 9 threaded preferably through one side of the said boss. The ferrule 5 is preferably tapered in the direction of its upper or outer end which end is preferably closed as indicated by the numeral 10, and the said ferrule may be of any suitable length and otherwise of any desired dimensions.

The section 4 of the head 2 is in the nature of a sleeve indicated by the numeral 11 and having its bore 12 tapered so as to more or less snugly receive the ferrule 5 as shown in Figs. 2 and 3 of the drawings. By reference to Fig. 3 it will be observed that the sleeve 11 is formed in its under side with a slot 13 opening through the lower end of the sleeve and more or less snugly receiving the boss 7 when the sleeve is fitted onto the ferrule 5. Due to the engagement of the side walls of the slot 13 against the opposite side faces of the boss 7, the sleeve 11 will be held against rotation upon the ferrule 5 and consequently the said sleeve 11 is supported in substantially the same manner as though fixed directly upon the end of the trolley pole 1 as is customary in the case of ordinary trolley heads. While the sleeve 11 is held against rotation or turning movement upon the ferrule 5, these parts may separate through relative movement in the direction of their lengths. Means, however, is provided for normally holding the two sections of the head assembled, the

means being, however, yieldable so as to permit of separation of the sections under emergency conditions as will be presently described. The holding means just referred to comprises detents, indicated in general by the numeral 14, arranged within housings 15 formed by providing the sleeve 11 with oppositely located bulges 16 at its lower end. Each of the detent devices 14 is in the nature of a leaf spring 17 riveted or otherwise secured at its inner end as at 19 within the respective housing 15 and normally sprung inwardly toward the axis of the said sleeve 11 and provided at its outer end with a head 20 having a beveled or rounded face 21, these faces of the heads of the two detent devices being presented toward each other as clearly shown in Fig. 2 of the drawings. The ferrule 5 is formed exteriorly at diametrically opposite points with seats 22 designed to receive the heads 20 in the manner shown in Fig. 2 of the drawings and it will now be understood that when the section 4 comprising the sleeve 11 is fitted onto the section 2 comprising the ferrule 5, the heads 20 of the detent devices will spring into engagement in the seats 22 and will thus serve to normally hold the parts assembled. However, due to the beveling or rounding of the faces 21 of the heads 20 and the corresponding formation of the seats 22, any pulling apart stress exerted upon the sections in the direction of their axes will result in the heads 20 of the detent devices riding out of their respective seats, thus permitting of the separation of the section 4 from the section 3. Inasmuch as the engagement of the boss 7 within the slot 13 serves to prevent rotation of the sleeve 11 upon the ferrule 5, the springs 17 of the detent devices will, of course, be relieved of any stress which would otherwise be imposed upon them if some means were not provided for preventing rotation of the said sleeve upon the ferrule. Furthermore, in assembling the parts there will be certainty of the heads 20 of the detent devices engaging in their seats when the sleeve 11 is so positioned that the boss 7 will enter the slot 13 as the parts are shoved together.

The section 2 comprising the sleeve 4, is provided at its upper end with a harp supporting head indicated in general by the numeral 23, this head having a flat supporting upper face 24 and being formed with an opening 25 extending vertically therethrough and at right angles to the said face 24. The harp is indicated in general by the numeral 26 and the same comprises a base portion 27 and upstanding cheek pieces 28 provided with bearings 29 at their upper ends for the reception of the ends of the trolley wheel spindle indicated by the numeral 30, the said wheel being indicated by the numeral 31 and being of the usual type.

The base 27 of the harp is formed with an opening 32, and a swivel bolt 33 is fitted through this opening and through the opening 25 so as to mount the harp 26 for turning movement upon the supporting face 24 of the head 23. A nut 34 is threaded onto the lower end of the bolt and is provided with an eye 35 for the connection of the usual pull rope (not shown) by which the pole may be lowered or swung downwardly against the tension of the usual springs which normally hold it in elevated position. In order that the trolley wheel 31 may be mounted in centered position between the cheek pieces 28 and in order that the electric current may be most effectually transmitted through the wheel to the harp and thence to the section 3 and finally to the section 1. Leaf spring bearing members 36 are secured to the inner faces of the cheek pieces 28 and are sprung inwardly with relation to the planes of these faces and are provided at their upper ends with ears 37 apertured for the passage of the spindle 30, these ears bearing against the opposite ends of the hub 90 of the wheel 31.

In order that the turning movement of the harp upon the head 23 may be limited, the head is formed at its forward side with an upstanding abutment lug 38, and the base portion 27 of the harp is formed at diametrically opposite sides with abutment lugs 39 adapted to strike the lug 38 for the purpose stated.

Having thus described the invention, what is claimed as new is:

1. A trolley pole head comprising a pole section, a harp section slidably fitted on the end of the pole section and having a longitudinal notch in its lower end, a connection for an electrical conductor carried by the pole section and engaging in said notch to prevent turning of the harp section with relation to the pole section, and means yieldably resisting sliding movement of the harp section.

2. A trolley pole head comprising a pole section, a harp section separably assembled therewith, and a resilient detent carried by one of the sections and coacting with the other section to yieldably resist separation of the sections, said detent being housed within the harp section in the normal position of the parts.

3. A trolley pole head comprising a pole section provided at its opposite sides with seats, a harp section slidably fitted on the pole section, means to prevent rotation of the harp section, and resilient detent members carried by the harp section and engaging in said seats to yieldably resist separation of the sections.

4. A trolley pole head comprising a pole section provided at its opposite sides with seats, a harp section slidably fitted on the

5 pole section, resilient detent members carried by the harp section and engaging in said seats to yieldably resist separation of the sections, the harp section being formed
10 with a longitudinal notch in its lower end, a projection on the pole section and engaging in said notch and preventing turning of the harp section upon the pole section and means for connecting an electrical conductor to said projection.

5. A trolley pole head comprising a pole section having diametrically opposite seats in its outer face, a harp section fitted loosely upon the pole section and provided at its

lower end with a longitudinal notch and 15 with longitudinal grooves in its inner surface out of alignment with said notch, leaf springs secured at their upper ends within the upper ends of said grooves and provided at their free ends with heads to engage the 20 seats in the pole section, a projection on the pole section fitting within the notch in the harp section to prevent rotation of the harp section, and means for securing an electrical conductor to said projection. 25

In testimony whereof I affix my signature.

SAMUEL S. COOPER. [L. s.]
